UNITED STATES PATENT OFFICE.

GUY BEEDLE, OF PROGRESSO, NEW MEXICO.

GATE.

1,307,996.

Specification of Letters Patent. Patented June 24, 1919.

Application filed December 26, 1917. Serial No. 208,991.

To all whom it may concern:

Be it known that I, GUY BEEDLE, a citizen of the United States, residing at Progresso, in the county of Torrance and State 5 of New Mexico, have invented certain new and useful Improvements in Gates; and I do hereby declare the following to be a full, clear, and exact description of the invention, such as will enable others skilled in the art 10 to which it appertains to make and use the same.

This invention relates to a gate, and particularly to a construction embodying an angle iron bracing for the slats thereof and 15 means for mounting the gate.

A further object of the invention is to provide an improved construction of hinging or pivoting means for a gate comprising eye-bolts through which a vertically disposed hinge rod extends, together with hinge straps encircling said rod and secured to the gate so as to rest upon the eye-bolts. 20

Other and further objects and advantages of the invention will be hereinafter set forth 25 and the novel features thereof defined by the appended claim.

In the drawings,

Figure 1 is a side elevation of the gate and mounting.

Fig. 2 is a detail section on the line 2—2 30 of Fig. 1.

Like numerals refer to like parts in the several figures of the drawings.

The gate as shown is composed of the 35 horizontal slats which are connected together by angle or other irons so as to be properly braced. An iron 17 is disposed at the hinge end of the gate and from the upper end thereof a binder iron 8 extends 40 diagonally downward to the lower free end of the gate where it is connected with a vertical iron 9 disposed parallel to the iron 17. Vertical brace irons 10, 11, 12 and 13 are connected to the slats and disposed to extend 45 from the diagonal iron 8 to the upper and lower edges of the gate.

The gate is hinged by means of the eye-bolts 3 and 4 inserted in a suitable post or

support and having a shoulder to limit the extent to which it may be driven therein. 50 At the upper portion of the post an eye-bolt 3 extends therethrough and is secured by a suitable nut. Extending through these eye-bolts is a hinge key or rod 16 which is held against downward movement by means 55 of a pin 18 and surrounding this rod are the hinge straps 5 and 7. The strap 5 is formed of a single piece of material bent upon itself to closely encircle the rod 16, while the ends thereof are offset apart 60 between the gate rails and provided with lateral or vertical T-heads or securing plates 20 adapted for attachment to and across the slat boards or rails of the gate in any desired manner. 65

Between the eye-bolt 4 and the strap bearing 5 a suitable steel wear ring 6 is disposed which carries the weight of the gate so as to avoid friction and wear of the co-operating members. The strap 7 is formed with 70 an encircling portion embracing the upper end of the rod 16 and suitably connected to the upper end of the iron 17. The gate structure is also provided with a latch 19 of any desired construction and with a lock 75 bolt 15 secured in position by the plate 14, as shown.

For the purpose of bracing the post and the gate carried thereby, a stay brace 1 is provided and secured at its upper end to the 80 eye-bolt 3. When formed of angle iron, this upper end of the brace is suitably flattened for that purpose. The brace is formed in sections so that the foot section 2 thereof may be properly anchored in the ground 85 and the brace members then adjustably secured together when the desired alinement of the post is obtained for the proper swinging action of the gate.

The construction and operation of the 90 gate and its hinge will be apparent from the foregoing description and the invention presents a simple, economically constructed and very efficient form of gate and hinge in which the gate slats are properly braced and 95 connected while the hinge members have an

extended bearing upon the vertical rod extending through the eye-bolts.

Having thus described my invention, what I claim as new is:—

- 5 A gate comprising slats, a hinge rod, and a hinge strap bent between its ends to closely encircle said rod and having its ends extending between two slats of the gate and offset apart, said ends of the strap being provided

with T-heads secured to the opposite sides 10 of said slats.

In testimony whereof I have signed my name to this specification in the presence of two subscribing witnesses.

GUY BEEDLE.
